United States Patent Office.

G. A. ENO, OF PHILADELPHIA, PENNSYLVANIA.

Design No. 2,596, dated March 19, 1867.

DESIGN FOR A SPOON HANDLE.

The Schedule referred to in these Letters Patent and making part of the same.

TO ALL WHOM IT MAY CONCERN:

Be it known that I, G. A. ENO, of Philadelphia, county of Philadelphia, State of Pennsylvania, have invented or produced a new and original Design for a Handle of a Spoon or other similar article; and I do hereby declare that the accompanying drawing, and the following explanation thereof, form a full, clear, and exact description of the said design.

In the accompanying drawing, the figure represents the handle of a spoon, ladle, fork, or other similar article. At the outer end of the handle A is a ball, *a*, which is fluted, as shown in the drawing, and at the side of this ball is an ornamental projection, *b*.

I claim the design for the handle of a spoon or other similar article, substantially as shown in and by the accompanying drawing.

In testimony whereof I have signed my name to this specification in the presence of two subscribing witnesses.
